UNITED STATES PATENT OFFICE

98,860

DESIGN FOR A VALANCED WINDOW-CURTAIN

Sidney S. Gutlon, Newton, Mass.

Application January 7, 1936, Serial No. 60,466

Term of patent 14 years

To all whom it may concern:

Be it known that I, Sidney S. Gutlon, a citizen of the United States, residing at Newton, in the county of Middlesex and State of Massachusetts, have invented a new, original, and ornamental Design for a Valanced Window-Curtain, of which the following is a specification, reference being had to the accompanying drawing, forming part thereof.

Figure 1 is a front perspective view of the valanced window-curtain; and
Figure 2 is an end view thereof.

I claim:

The ornamental design for a valanced window-curtain substantially as shown.

SIDNEY S. GUTLON.
